(57) **CLAIM**

The ornamental design for a weight handle, as shown and described.

DESCRIPTION

FIG. 1 is a perspective view of the weight handle;
FIG. 2 is a left-side view of the weight handle;
FIG. 3 is a right-side view of the weight handle;
FIG. 4 is a rear view of the weight handle;
FIG. 5 is a front view of the weight handle;
FIG. 6 is a top view of the weight handle;
FIG. 7 is a bottom view of the weight handle; and,
FIG. 8 is an exploded view of the weight handle.
The broken lines depict portions of the weight handle that
form no part of the claimed design.
